4 Claims. (Cl. 195—28)

The present invention relates to a method of producing 5-amino-4-imidazolecarboxamide ribofuranoside (hereinafter referred to AICAR) by fermentation.

AICAR is being used as an intermediate for synthesizing components of nucleic acid, which are valuable as seasonings, and is also a raw material for synthesizing pharmaceuticals.

It is known that AICAR can be produced on an industrial scale by fermentative processes in which certain mutants of *Bacillus subtilis* or *Bacillus megatherium*, are cultured on a nutrient medium containing a carbon source, a nitrogen source, and other nutrients, and AICAR is recovered from the culture broth.

The known AICAR fermentation method is often interfered with by excessive bacterial growth or metabolism and by spore formation.

We have found that AICAR fermentation can be improved by the presence of small amounts of alkanoic acids in the culture medium, which control spore formation and increase the yield of AICAR.

The alkanoic acids which can be used in the present invention have three to nine carbon atoms in straight or branched chains and include propionic acid, butyric acid, caproic acid, and pelargonic acid. The minimum concentration of the acid which produces measurable beneficial effects is determined by the precision of the measuring method. The improvement is commensurate with the amount of alkanoic acid at very low concentration, but reaches a maximum at a concentration of about 100 mg./dl. for butyric acid and at similar values for the other acids of the invention as far as they are soluble. Some improvement is still observed at concentrations much higher than the optimum concentration.

Table 1 shows the effects of representative alkanoic acids on AICAR fermentation. All tests were performed with a culture medium of the following composition:

Glucose	g./dl.	8
KCl	g./dl.	0.1
MgSO ₄ ·7H ₂ O	g./dl.	0.04
Fe	p.p.m.	2
Mn	p.p.m.	2
Casein hydrolysate	pct.	0.2
Yeast nucleic acid	g./dl.	0.1
NH ₄ Cl	g./dl.	1.5
CaCO ₃	g./dl.	5

Alkanoic acid as stated in Table 1.

20 ml. batches of the medium were placed in 500 ml. shaking flasks and inoculated with *Bacillus megatherium* MA-336 (ATCC No. 15117) and cultured at 30° C. for 48 hours.

Bacterial growth was measured by the specific optical density of a specimen diluted with water to 50 times its original volume to light of wavelength 562 m μ . Spore formation was evaluated by counting spores and cells in a microscopic field, and the percentage of spores was calculated on the basis of the combined number of spores and cells. The AICAR produced was determined in the culture broth by the method of Bratton-Marshall.

TABLE 1

Acid	Mg./dl.	Op. density	Spores, Percent	AICAR, g./dl.
Propionic	10	0.76	20	0.81
Do	30	0.76	2	0.93
Do	50	0.79	0	0.93
Butyric	10	0.80	50	0.94
Do	30	0.75	0	1.01
Do	50	0.85	0	0.90
Caproic	10	0.84	0.3	0.95
Do	20	0.86	0	0.90
Enanthic	15	0.85	0	0.85
Caprylic	5	0.88	0	0.90
Do	10	0.87	0	0.85
Pelargonic	2.5	0.87	0	0.95
Control	0	0.80	17	0.74

As is apparent from the table, butyric acid is superior to other alkanoic acids in controlling spore formation and increasing the yield of AICAR.

The soluble salts of alkanoic acids having 3 to 9 carbon atoms are as effective as equivalent amounts of the corresponding free acids.

The composition of the culture medium is otherwise not critical and the usual carbon and nitrogen sources are employed.

The time after inoculation at which the alkanoic acid or its salt is added to the culture medium has a distinct influence on the results obtained as is evident from the typical data on butyric acid (30 mg./dl.) of Table 2. Specific optical density was determined (1) at the time of butyric acid addition and (2) 48 hours after inoculation. Residual sugar was measured by the Lehmann-Schoell method at the time of butyric acid addition only, and spores and AICAR were determined when fermentation was terminated 48 hours after inoculation.

TABLE 2

Acid added after—	Residual sugar, percent	Optical density		Spores, percent	AICAR, g./dl.
		(1)	(2)		
0 hrs.	100	0.04	0.82	0	1.01
4 hrs.		0.06	0.80	0	1.04
3 hrs.		0.08	0.80	0-1	1.02
12 hrs.		0.07	0.77	0-1	1.06
16 hrs.		0.09	0.76	1-2	0.96
20 hrs.	85.0	0.45	0.73	12	0.92
24 hrs.	70.0	0.60	0.74	73	0.84
80 hrs.	63.0	0.70	0.73	62	0.84
Not added			0.82	41	0.70

As is shown in Table 2, the acid is preferably added to the culture medium not later than 20 hours after inoculation and while the residual sugar present is at least 75% of the original value.

The bacteria whose production of AICAR benefit substantially from the present invention include *Bacillus megatherium* MA-336 (ATCC No. 15117), *Bacillus megatherium* MA-658 (ATCC No. 15118), *Bacillus subtilis* D-422 (ATCC No. 15115), and *Bacillus subtilis* D-2511 (ATCC No. 15116). All members of the family *Bacillus* which produce AICAR by fermentation were found to give at least slightly better AICAR yields with the acids of this invention than without.

Mutants induced from the afore-mentioned strains and lacking the ability of spore formation produce AICAR in high yields in the presence of the alkanoic acids and salts of this invention.

EXAMPLE 1

A seed culture was prepared on a culture medium containing 8 g./dl. starch acid hydrolysate (glucose equivalent), 0.1 g./dl. KCl, 0.04% MgSO₄·7H₂O, 2 p.p.m. each of Fe and Mn ion, 0.2 g./dl. casein hydrolysate, 0.13 g./dl. yeast ribonucleic acid (containing 80% pure ribonucleic acid), 1.5 g./dl. NH₄Cl, and 5 g./dl. CaCO₃ and sterilized at 115° C. for 10 minutes which was inoculated with a loopful of *Bacillus megatherium* MA-336 (ATCC No. 15117), and cultured at 30° C. for 20 hours with shaking.

Fresh culture medium of the above composition was mixed with 30 mg./dl. butyric acid, and 20 ml. batches of the mixed medium were placed in 500 ml. shaking flasks and sterilized at 115° C. for 10 minutes. 0.1 ml. of the seed culture was added to each batch, and the culture was incubated at 30° C. for 60 hours when the AICAR concentration in the broth reached 1.2 g./dl.

A control batch without butyric acid produced 1.05 g./dl. under otherwise identical condition, and the fermentation was not completed after 60 hours because of spore formation.

EXAMPLE 2

The procedure of Example 1 was repeated but starch hydrolysate, KCl and butyric acid were replaced by 8 g./dl. glucose, 0.01 g./dl. KH₂PO₄, and 15 mg./dl. caproic acid, respectively. The cultured broth contained 1.15 g./dl. AICAR after 60 hours.

40 to 45 percent spores formed in a control batch without caproic acid, the fermentation was not completed in 60 hours when the culture broth contained only 0.95 g./dl. AICAR.

EXAMPLE 3

Bacillus subtilis D-2511 (ATCC No. 15116) was inoculated on the medium of Example 1, cultured at 30° C. for 25 60 hours, and AICAR was produced to a concentration of 0.6 g./dl.

A control batch without butyric acid contained 0.4 g./dl. AICAR, and the fermentation was not completed in 60 hours.

EXAMPLE 4

Seed cultures of *Bacillus megatherium* MA-336 were prepared on eight 50 ml. batches of the medium of Example 1 in Sakaguchi flasks which were sterilized at 115° C. for 10 minutes, inoculated with a loopful of *Bacillus megatherium* MA-336, and cultured until the specific optical density reached 0.20.

Twenty liters of fermentation medium having the same composition as in Example 1 except for CaCO₃ were poured into a 40 liter fermentor, sterilized at 110° C. for 10 minutes, and mixed with 6 g. of sterilized butyric acid. The medium was inoculated with the seed cultures and incubated at 30° C. with stirring at 300 r.p.m. while aerating at 1/4 volume per minute. The pH of the medium was maintained within a range between 5.8 and 6.0 by adding ammonia to the air. The fermentation was terminated when samples showed no further increase of AICAR.

The AICAR concentration reached 1.32 g./dl. 50 hours after inoculation while the residual sugar was reduced to 8%. After 60 hours, there were 1.26 g./dl. AICAR and

7% residual sugar. A control test without butyric acid showed only 0.87 g./dl. AICAR and 18% residual sugar after 60 hours. There were 50% spores in the control test, none in the presence of butyric acid.

EXAMPLE 5

Culture media containing 8 g./dl. starch acid hydrolysate (glucose equivalent), 0.08 g./dl. KCl, 0.04 g./dl. MgSO₄·7H₂O, 2 p.p.m. of Fe and Mn ion, 0.09 g./dl. yeast ribonucleic acid, 1.7 g./dl. NH₄Cl, 2.5 g./dl. CaCO₃, and butyric acid as listed below were prepared, the pH of the media was adjusted to 7.2 with aqueous ammonia, and 20 ml. batches were placed in 500 ml. flasks.

After sterilizing at 115° C. for 5 minutes, each medium was inoculated with a loopful of *Bacillus megatherium* 336-M-1 which had been induced from *Bacillus megatherium* MA-336 (ATCC No. 15117) and had lost the ability of spore formation, and cultured at 30° C. for 65 hours, whereupon the amount of AICAR produced was 20 determined.

Butyric acid, mg./dl.	Optical density	AICAR, g./dl.
0	0.55	0.97
50	0.55	1.07
80	0.57	1.02
100	0.58	1.20
130	0.49	1.10
160	0.54	1.08
200	0.54	1.06

What we claim is:

1. In a process of producing 5-amino-4-imidazolecarboxamide ribofuranoside by fermentation of an aqueous culture medium with a bacterium of the genus *Bacillus* capable of producing 5-amino - 4 - imidazolecarboxamide ribofuranoside, the improvement which consists in adding to said culture medium an alkanoic acid having 3 to 9 carbon atoms or a salt of said acid which is soluble in said medium.

2. In a process as set forth in claim 1, said acid being butyric acid.

3. In a process as set forth in claim 2, the concentration of said butyric acid in said medium being between 10 and 200 milligrams per deciliter.

4. In a process as set forth in claim 3, said bacterium being a member of the species *Bacillus megatherium* and *Bacillus subtilis*.
